US0D1086801S

(12) **United States Design Patent** (10) Patent No.: **US D1,086,801 S**
(45) Date of Patent: ** Aug. 5, 2025

(54) **POD FOR USE WITH A FOOD OR DRINK MACHINE**

(71) Applicant: **ColdSnap, Corp.**, Billerica, MA (US)

(72) Inventors: **Matthew Fonte**, Concord, MA (US);
Nicholas Fonte, Sudbury, MA (US)

(73) Assignee: **ColdSnap, Corp.**, Billerica, MA (US)

(**) Term: **15 Years**

(21) Appl. No.: **29/911,921**

(22) Filed: **Sep. 11, 2023**

(57) **CLAIM**

The ornamental design for a pod for use with a food or drink machine substantially as shown and described.

DESCRIPTION

FIG. 1 is a perspective view of a pod.

FIG. 2 is another perspective view of the pod of FIG. 1.

FIG. 3 is a front view of the pod of FIG. 1. The back, right side, and left side views are the same as the front view.

FIG. 4 is a top view of the pod of FIG. 1; and,

FIG. 5 is a bottom view of the pod of FIG. 1.

The broken lines which define the bounds of the claimed design form no part thereof.

1 Claim, 2 Drawing Sheets
